UNITED STATES PATENT OFFICE.

ALBERT C. CARTER, OF NORWOOD, OHIO, ASSIGNOR, BY MESNE ASSIGNMENTS, TO THE CHAMPION CONSERVER COMPANY, OF CINCINNATI, OHIO.

CARBON CONSERVER.

Application filed May 16, 1923. Serial No. 639,321.

To all whom it may concern:

Be it known that I, ALBERT C. CARTER, a citizen of the United States, residing at Norwood, in the county of Hamilton and State of Ohio, have invented certain new and useful Improvements in Carbon Conservers, of which the following is a specification.

This invention relates to carbon paper conserving devices for use upon typewriting and similar machines and to that type of such devices in which carbon paper is rolled upon a roll and is unwound therefrom as used.

In the ordinary use of carbon paper for manifolding, in which sheets are used of the same size as the sheets of paper being written upon, it usually happens that the central part of the carbon sheet is exhausted before the ends have been used very much, owing to the fact that many letters do not cover a whole page, and also because the portion of the carbon which comes opposite the letter head is not written upon.

An object of my invention is to support a roll of carbon paper in such manner that the carbon can be readily inserted between the sheets after they are inserted into the machine, and in this manner, the portion of the carbon which comes opposite the lower part of the letter sheet, will not be wasted. As soon as the end of the carbon sheet, which has been repeatedly used becomes exhausted, it can be torn off and fresh carbon presented in writing position.

Another object of the invention is to provide a support for the carbon roll that can be easily mounted upon a typewriting machine without any change in the machine, and as readily detached therefrom.

A further object is to provide such a support which can be folded into compact relation to the machine when it is desired to inclose it in a case or close it up in the usual desk.

A still further object is to provide means for supporting the carbon roll which will enable its quick removal when it is desired to use a new carbon roll for any purpose.

Other objects will be apparent from the following detailed description and appended claims.

In the drawings:

Figure 1 is a rear view of the attachment in operative position with relation to a typewriting machine of conventional design. 55

Figure 2 is a similar view showing the attachment folded to compact position.

Figure 3 is a side view of the attachment when swung to an inclined position for the better handling of long sheets of paper. 60

Figure 4 is a front view of the device when detached from the machine.

Figure 5 is a fragmentary view showing the means of supporting the device of Figure 4 on the machine. 65

Figure 6 is a sectional view through the carbon roll and the end pieces that engage the same.

Figure 7 is a perspective view of one end piece. 70

Figure 8 is a perspective view of the other end piece.

Figure 9 is an end view of either end piece looking from the inner end. 75

Figure 10 is a perspective view of the core upon which the carbon is wound.

The drawings show the frame A of a conventional typewriting machine, the present illustration being substantially that of the Underwood machine, although the attachment is in no way limited thereto. The supporting frame for the attachment comprises a bar 1 having inclined ends 2 which are bent to embrace one side of a rod B in the machine. Short pieces 3 have their ends similarly bent to embrace the other side of the rod B, and screws 4 pass through the two bars 1 and 3 and hold them in engagement with the bar B. The rear ends of the side members or bars 1 are connected by a U-shaped member 5 having relatively short vertically extending arms 6 formed with open bearings 7. Somewhat in front of the member 5, the side bars 1 are connected by a cross bar 8. Near the center of the bar 5 it is provided with downwardly extending ears 9 in which is mounted a roller 10. This roller is designed to run on a track 11 which is attached to the frame of the typewriter through two side arms 12 riveted or suitably fastened to the track bar 11, or made integral therewith. The screws 13 which are used to hold these arms 12 in place are

90
95
100

screws that are already in the machine. It will thus be noted that by removing two screws 13 and loosening two screws 4, the whole device may be immediately detached 5 from the machine.

Supported in the frame already described is a frame composed of a base bar 14, two side bars 15 and a cross bar 17 located near the top of the side bars. These side bars 10 are provided with headed studs 16 which are adapted to fit into the open end bearings 7 and thus support the frame for pivotal movement. The bar 17 is provided with a serrated lower edge 18 for the purpose 15 of tearing off the used portion of the carbon paper when desired.

Near the center of the bar 14 is provided a bearing 19 in which rotates a catch having a horizontal portion, a front arm 20 and a rear arm 21 somewhat longer than the front arm. When the parts are in the position shown in Figure 1, this catch is turned so that the arms 20 and 21 pass down on opposite sides of the bar 5 and thus hold the 25 frame in upright position. When it is desired to hold the parts in the Figure 3 position, the catch is disengaged from the bar by turning it and the support is tilted backwardly to a slight degree. The catch 30 is then turned downwardly again and the longer arm 21 will engage a notch 22 in the bar 8 and hold the parts in the Figure 3 position. If it is desired to hold the attachment, the catch is disengaged and the 35 frame moved forward to the position shown in Figure 2.

A U-shaped member is formed by a transverse bar 23 and side bars 24 and this member is pivoted to the bars 15 by screws 25 40 which may be any desired form of fastening that will hold the parts for pivotal movement but frictionally retain the member in desired position, as shown for example in Figure 1. When the attachment is used in 45 its inclined position, as in Figure 3, this member is preferably moved to a position in which it nests within the frame bars 15.

The upper ends of the bars 15 are provided with open bearings 26 such as illustrated, or any other equivalent form of 50 bearing may be used as desired. It may be found preferable in some cases to provide keepers to close the open bearings, but this is immaterial so long as the carbon roll 55 supports can be quickly removed or replaced.

The carbon C is preferably wound upon a core 27 of any suitable material, and this core is provided with one or more notches 60 28 at each end. This core is made much larger than is usually the case in order that the carbon wound upon it will not have the tendency to curl when unwound that it would have in the case of a small core. 65 The core is supported by two end pieces

29 and 30, which may ordinarily be interchangeably used. In the form illustrated, the end piece 29 is provided with a spring for returning the carbon unrolled, and is shown as located at the left hand side of the 70 machine.

Each end piece has a large disk 31 through the center of which passes a spindle 32 retained in position by a nut 33 screwed on the end thereof, washers 34 being interposed as desired. The body of the end piece is a substantially cylindrical member 35 having its edges spun over the disc 31 or in any other suitable manner attached thereto. On the cylindrical member 35 is provided a lug 36 which is adapted to engage one of the notches 29 when the cylindrical portion is placed within the core 27. These end pieces may be formed of sheet metal stamped or spun to appropriate form. 75 Each spindle is provided with a knurled finger piece 37. About one spindle is coiled a spring 38, one end being passed through a hole in the finger piece 37 as shown in Figure 7, while the other end extends downwardly along side of the bar 15 and is retained in a strap bearing 39 as shown in Figures 1 and 2. This permits the end of the spring to move out of the strap bearing 39 when the carbon roll is removed, by simply lifting up on the same. This spring is provided to roll up the carbon that is being used whenever writing on one sheet 85 has been finished and the feed rolls of the typewriter are released for the removal of the written matter. It is not essential and the attachments may be used without the spring and with two end pieces such as 90 shown in Figure 8.

Attached to about the middle of the bar 105 17 is an upwardly extending member 40 of spring sheet metal formed at its free end to hold a short rod 41 which carries at each end a rubber surfaced roll 42 that is adapted to bear against the carbon on the roll with light pressure. This tends to hold the roll 110 against accidental movements, avoids unwinding of the carbon when the device is not in use and conduces to a more even 115 operation of the device.

The operation of the attachment is obvious. When the parts are in the position shown in Figure 3 for example, the carbon C passes between the original sheet O and the duplicate or copy sheet D. This is the 120 position preferably adopted for long sheets. If the attachment is used in its vertical position as shown in Figure 1, the carbon preserves the same relation to the original and copy sheets, and at this time the support 23 is preferably moved into the position shown where it furnishes a rest for the ends of the loose copy sheets which may be of light material. Whenever the writing on a sheet is 125 finished and the feed rolls of the typewriter 130

are thrown off, the spring 38, if employed, rewinds the carbon on the roll from whence it is drawn for the next operation. If the spring 38 is not employed, the operator 5 merely twirls one of the finger pieces 37 quickly and thus rolls up the carbon. The pressure of the rolls 42 against the carbon roll will prevent any overthrow and also cause the carbon to wind properly on the 10 roll. Whenever the end portion of the carbon sheet is exhausted, it will be torn off across the serrated edge of the bar 17.

It will be understood that rolls of carbon will be provided consisting of one, two 15 or more sheets, for use when it is desired to make one, two or more carbon copies, and the operator can change from one roll to the other merely by lifting out one carbon roll from its bearings and dropping the next 20 one into place. When closing the machine for any purpose the attachment will be folded into the position shown in Figure 2, or it may be removed by lifting the frame out of the open bearings 7.

25 The device is very light but the track provided therefor prevents any additional weight from being imposed on the carriage. It is obvious that the exact form of the attaching members 1 may be modified somewhat for application to different types of 30 machines, and the method of supporting the track 11 will also be varied as required. Such changes in no way depart from the spirit of the invention. Many other detail 35 changes in the precise form of the structure may be made and it is to be understood that the invention is limited only by the scope of the appended claims.

I claim as my invention:

40 1. A carbon roll attachment for typewriting machines comprising a member attached to the carriage of the typewriting machine and having open end bearings, a frame having projections pivotally mounted in said 45 bearings, a movable catch carried by said frame and adapted to engage said member to hold the frame in different operative positions, and means for supporting a carbon roll in the upper part of said frame.

50 2. A carbon roll attachment for typewriting machines comprising a member attached to the carriage of the typewriting machine, and having bearings, a frame having projections pivotally mounted in said bearings, 55 a catch carried by the frame and adapted to engage said member to hold the frame in different positions, or to be disengaged to permit the frame to fold, means for supporting a carbon roll in the upper part of said frame, and a cross-bar near the upper 60 end of the frame across which the carbon may be torn.

65 3. A carbon roll attachment for typewriting machines comprising a support attached to the carriage of the typewriting machine

and including a U-shaped member with open end bearings, a frame having projections engaged in said bearings, a track on the carriage, a roll on the U-shaped member to engage the track, a catch for holding the frame 70 in vertical or inclined position, and means for supporting a carbon roll in said frame.

4. A carbon roll attachment for typewriting machines comprising a support attached to the carriage of the typewriting 75 machine and including a U-shaped member with open bearings in its upper ends and a transverse bar, a frame having means to pivotally engage the open bearings, a catch carried by said frame and engaging the U-shaped member to hold the frame in one position and the transverse bar to hold it in another position, a track for supporting the weight of the attachment, and means for supporting a carbon roll in said frame. 80

5. A carbon roll attachment for typewriting machines comprising a support carried by the carriage of the typewriting machine, a track carried by the machine frame, a frame mounted for pivotal movement to a plurality of positions in the support, a catch carried by said frame and adapted to hold it in a plurality of positions, a roller carried by said support and engaging the track, and means for supporting a carbon roll in 95 the frame.

6. A carbon roll attachment for typewriting machines comprising a support carried by the carriage of the typewriting machine, a track on the machine frame, a frame pivotally mounted in said support, and having its weight supported on said track, means carried by the frame and engaging the support to hold the frame in a plurality of different positions or to permit its folding to 100 compact position with reference to the machine, and means for supporting a carbon roll in said frame.

7. A carbon roll attachment for typewriting machines comprising a support carried by the carriage, a frame pivotally mounted therein, means for holding said frame in a plurality of operative positions in said support, means for supporting a carbon roll in 110 said frame, a paper rest carried by said frame, a transverse bar connecting the sides of the frame and having an edge across which the carbon may be torn.

8. A carbon roll attachment for typewriting machines comprising a support carried by the carriage, a frame pivotally mounted therein, means for supporting a carbon roll in the upper part of the frame, a transverse bar adjacent the carbon roll, a spring member attached to the bar, and a carbon engaging element carried by said spring member. 120

9. A carbon roll attachment for typewriting machines comprising a frame supported upon the carriage of the typewriting ma- 125 130

chine, means for holding a carbon roll therein, a transverse bar adjacent the carbon roll, a flat yielding member carried by said bar, and carbon engaging elements carried by said member.

10. A carbon roll attachment for typewriting machines comprising a frame supported upon the carriage of the typewriting machine, means for holding a carbon roll therein, a transverse bar adjacent the carbon roll, a resilient support carried by said bar, and rolls carried by said support in position to engage the carbon roll.

11. A carbon roll attachment for typewriting machines comprising a frame mounted to travel with the carriage of the typewriting machine, means for supporting a carbon roll therein, said means com-

prising end pieces having spindles, a spring connected to one spindle and to the frame 20 which tends to rewind the carbon on the roll, and means carried by the frame and yieldably engaging the carbon roll to prevent too free movement thereof.

12. A carbon roll attachment for typewriting machines comprising a frame mounted to travel with the carriage, means for holding the frame in a plurality of operative positions, a bar carried by the frame and having an edge across which the carbon 30 may be torn, means for supporting a carbon roll in said frame, and members carried by the bar and resiliently engaging the carbon roll.

In testimony whereof I affix my signature.
ALBERT C. CARTER.
